CLAIM

The ornamental design for a double nail puller with nailer, as shown and described.

DESCRIPTION

FIG. 1 is a side elevational view of the double nail puller with nailer showing my new design, the opposite side being identical;

FIG. 2 is a top plan view thereof;

FIG. 3 is a bottom plan view thereof;

FIG. 4 is a front perspective view thereof.

*FIG. 1.**FIG. 2.**FIG. 3.**FIG. 4.*
